ATTORNEY'S

UNITED STATES PATENT OFFICE.

EDWIN FLEMING TREVAIL, OF JOHANNESBURG, TRANSVAAL, SOUTH AFRICA.

ADVERTISING DEVICE.

1,355,716.

Specification of Letters Patent.

Patented Oct. 12, 1920.

Application filed June 12, 1919. Serial No. 303,579.

To all whom it may concern:

Be it known that I, EDWIN FLEMING TREVAIL, a British subject, residing at 25^a 7th avenue, Bezuidenhout Valley, Johannesburg, Transvaal Province of the Union of South Africa, have invented certain new and useful Improvements in Advertising Devices, of which the following is a specification.

10 The present invention has reference to apparatus for exhibiting pictures and particularly to apparatus such as is employed for advertising, in which the exhibited picture is periodically and automatically 15 changed. The term picture is used in this specification in a wide sense as including pictorial matter, letter press and the like.

The apparatus forming the subject of this application presents a picture for a period, 20 causes it to fade out—usually by progressive and gradual blurring and without substantial variation of the illumination,—and then again brings a picture (usually the next of a series) into view in the reverse manner.

25 The apparatus is simple and compact and may thus be attached for exhibition to the external wall of a building. It enables a picture series of indefinite length to be shown and permits the number or sequence 30 of the series readily to be altered.

In the accompanying drawings:—

Figure I is a sectional elevation of the plane I—I, Fig. IV.

Fig. II is a sectional elevation of the plane 35 II—II, Fig. IV.

Fig. III is a sectional elevation of the plane III—III, Fig. IV.

Fig. IV is a plan sectioned on IV—IV Fig. I.

40 Fig. V shows the picture sheets.

1 indicates a frame which may be secured in front of an opening 2 in the wall 3 of a building. 4 is a box of which the frame 1 forms the front and which incloses the 45 mechanism and the pictures.

The box is provided with doors such as 5, for giving access to the interior. Said box is detachably secured to the frame by fastenings 6 and is fitted with casters 7 so 50 that it can readily be withdrawn from and re-secured to the frame 1 when desired.

In the frame 1 is mounted a translucent window 8 which may be coarsely ground glass or glass covered with thin paper. 9 is 55 a transparent picture illuminated from be-

hind by lamps 10. The picture is exhibited by pressing it against the translucent window 8, when, provided the interior illumination is greater than the exterior illumination, the picture is clearly visible. 60 Upon now withdrawing the picture slowly from the window it is seen to become blurred and finally all definition is lost, the window showing simply an illuminated blank. Upon reversing the process and gradually 65 moving a picture up to the window until it is finally pressed against the same, the picture gradually takes form and comes into focus very similarly to the focusing of a picture by means of a lens. In showing a series 70 of pictures the change of picture is made while the picture is retracted from the window, when it is, for all practical purposes invisible.

The pictures are conveniently cotton 75 sheets painted with transparent colors. Adjacent sheets are secured to a common slat 11, Fig. V, by hemming and indenting the ends 12 as shown and passing the slat 11 through the hems. A pin 13 at each end 80 keeps the slat in place. In this way an endless picture band of indefinite length is formed, such as to permit any part of it to be readily altered by the insertion, withdrawal, and substitution of one or more picture sheets 9.

14 is a carriage over which the picture band is looped and which is mounted to slide in guides 15 for movement toward and from the window 8. It is provided at the front 90 with a glass or similar sheet 16, in front of which the picture for exhibition is positioned, and which serves to press said picture against the window 8. In order that the glass sheets 8 and 16 may be pressed together without danger of fracture the sheet 8 may be supported by a rubber cushion 17.

For reciprocating the carriage there is provided a crank 18 journaled in the box 4 and rotated in the direction of the arrow by 100 any suitable means such as the motor 19. The crank rotates slowly, say twice each minute. On it is a crank pin 20 which, during part of the revolution of the crank, co-operates with a cam surface 21, 22, 23, 24, 105 25 formed in the carriage 14. The shape of the latter is such that the pin 20 first engages the part 21 and withdraws the carriage 14 from the window 8 slowly in order to avoid too rapid disappearance of the pic- 110

ture. Thereafter the pin 20 engages the cam part 22 whereby the carriage is fully withdrawn at faster rate. When the carriage is fully withdrawn it is so held by 5 making the part 23 of the cam surface an arc of the circle traversed by the pin 20; and during this period of the cam the picture is changed. The pin thereafter engages the cam parts 24 and 25 which are the 10 reverse of parts 22 and 21 respectively, so that the new picture is carried up to the window 8 with a motion which is at first rapid and then slows up to cause the picture to come into definition with agreeable grad- 15 ualness. The picture remains in view while the crank is moving from the cam part 25 back to the cam part 21.

For the purpose of changing the picture a traveler 27 is mounted to slide vertically 20 at the back of the box 4 in guides 28. Forwardly from the traveler project the two fingers 29 and upon the traveler being pulled down while the carriage 14 is at the back of its travel, the said fingers engage one of 25 the slats 11, and carry it down the length of one picture, so pulling the next picture up into place in front of the glass 16. In order to make the carriage 14 short from front to back in relation to the height of the 30 picture, the picture band is doubled over idler rollers 30 at the top of the carriage frame. The slack of the band folds down into the bottom of the box 4, as indicated at 9^a, so that any length of band can be 35 accommodated.

For reciprocating the traveler 27 an arm 31 pivoted to the box 4 at 32 is rocked back and forth by a second crank 33, the pin 34 of which engages lugs 35 on the arm 31. Said arm carries a toothed segment 36 gearing 40 with a pinion 37 fast with a drum 38. A cord 39 is wound on the drum and its two ends are carried by guide rollers 40 to opposite sides of the traveler 27. The pin 34 drives the arm 31 rearward during the 45 period that the carriage 14 is retracted and stationary; and it drives the arm forward at any convenient time while the picture is showing. Movement of the carriage 14 to its forward position withdraws the slats 11 clear of the fingers 30, so enabling the latter to be raised without moving the slats.

It is sometimes desirable, in order to mask strong colors in a picture while the 55 same is being changed, to illuminate the front of the picture during its changing movement. For this purpose there are provided lamps 26 which are shut off from the picture by the carriage 14 when the latter 60 is at the forward point of its travel, but which throw light onto the front of the

picture when the same is sufficiently withdrawn.

I claim:

1. In a picture exhibiting apparatus, a 65 translucent window, a picture carrier movable toward and from the window to press a picture against the window, and means whereby a different picture will be pressed against the window at each forward movement of the carrier.

2. In picture exhibiting apparatus, a translucent window, a picture band comprising a succession of pictures, means to 75 press a picture in contact with the window and to withdraw the same and means to feed the picture band when so withdrawn.

3. In picture exhibiting apparatus, a translucent window, a picture, means to advance said picture to the window for exhibition and to withdraw the same, said means causing the final advancing movement and initial withdrawing movement to be slow in relation to the rest of the movement.

4. In picture exhibiting apparatus, a 85 translucent window, a carriage reciprocable to and from the window, a transparent front to said carriage, a picture movably mounted between said window and said transparent front, and means to reciprocate 90 the carriage to press the picture on the transparent front.

5. In picture exhibiting apparatus, a transparent window, a carriage reciprocable to and from the same, a picture band on the 95 carriage a traveler positioned for engagement with the picture band when the carriage is retracted from the window and means to reciprocate the traveler synchronously with the reciprocation of the carriage.

6. In picture exhibiting apparatus, a translucent window, a transparent picture, illuminating means behind the picture, means to advance the picture to the window 105 and to withdraw the same therefrom and means effective upon withdrawal of the picture to illuminate the front of the picture.

7. In a picture exhibiting apparatus, a casing having a translucent window, a reciprocating carriage in the casing and carrying a transparent member at its front, means on the carriage for supporting a picture band to permit it to pass in rear of the window, means for reciprocating the carriage, and means, whereby the picture band may be moved between the window and transparent member.

In testimony whereof I affix my signature.

EDWIN FLEMING TREVAIL.
